STARTER DRIVE

Raymond J. Quigley, Ann Arbor, Mich.

Application July 11, 1936, Serial No. 90,243

6 Claims. (Cl. 74—9)

The present invention appertains to new and useful improvements in starter drives.

The principal object of the present invention is to provide a simple and positive acting drive for engine starters.

Another important object of the invention is to provide a starter drive which is of low cost to manufacture and wherein the parts are capable of quick assembly as well as disassembly for the purpose of repair or replacement of defected parts.

Other important objects and advantages of the invention will become apparent to the reader of the following specification.

In the drawings:—

Figure 1 represents a side elevational view of the drive.

Figure 2 is a longitudinal sectional view through the drive.

Figure 3 is a section on the line 3—3 of Figure 2.

Figure 4 is an end elevational view of the drive.

Figure 5 is a side elevational view of the pinion assembly with a portion thereof broken away.

Figure 6 is a side elevational view of the splined sleeve with a portion broken away.

Figure 7 is a longitudinal sectional view through the barrel.

Figure 8 is a sectional view through the two sections of the split abutment wedge.

Referring to the drawings wherein like numerals designate like parts, it can be seen that numeral 5 denotes the starter motor shaft on which the elongated barrel 6 is located. One end of this barrel 6 is provided with the threaded radial bore 7 for the reception of the set screw 8 which is provided with a reduced extension adapted to be driven into a recess in the shaft 5. Numeral 9 is a lock screw for the set screw 8. Thus the barrel 6 is positively secured to the shaft 5. Removable pintles 10—11 are disposed in radial directions outwardly through the wall of the barrel 6 so as to project beyond the periphery thereof and engage into the spiral grooveways 12—13 of the splined sleeve 14. This sleeve 14 is slideable on the enlarged end portion A of the barrel 6 and on the internal wall 15 of the pinion assembly generally referred to by numeral 16.

One end of the sleeve 14 is provided with splined teeth 17 for engagement with the spiral grooveways 18 on the inside of the outer wall 19 of the pinion assembly 16.

The pinion gear assembly 16 as shown consists of the pinion 20 having the aforementioned spaced inner and outer walls 15—19 between which is located the ring 21 of cushion rubber. A gasket 55 22 of metal is interposed between this ring 21

and the spline toothed end of the sleeve 14. A lock ring 23 is provided at the inside of the wall 19 to prevent displacement of the toothed end of the sleeve 14 from the pinion assembly 16.

When the sleeve 14 is in the dotted line position shown in Figure 2, the spring-pressed pawl 24 is engaging into the recess 25 at the inside of the sleeve 14 so as to retain this sleeve as well as the pinion assembly in retracted position away from the flywheel (not shown).

Thus it can be seen, that when the shaft 5 starts rapidly into operation, rotation of the barrel 6 with the shaft 5 will cause the pintles 10 to ride in the grooveways 12—13 of the sleeve 14, projecting the sleeve 14 to the left of Figure 2 15 and shoving the pinion assembly 16 into mesh with the flywheel gear (not shown).

The cushion rubber ring 21 takes up some of the shock of this sudden action.

The pinion assembly stops against the abutment assembly generally referred to by numeral 26, which consists of a collar 27 having an internal annular grooveway 28. Numeral 29 represents a pair of semi-circular ring sections of transverse beveled construction each provided with ribs 30 at its inner side for engagement with circumferential grooveways on the adjacent end of the barrel 6. To assemble this abutment, the hollow end portion of the collar 27 is slipped over the sections 29 with the ribs thereof engaging into the grooveways of the barrel 6. When the collar 27 has been engaged sufficiently over the sections 29 so that the spring-pressed ball 31 engages into the grooveway 28, the abutment assembly will be intact and fixed on the barrel 6.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:—

1. A starter drive comprising a drive shaft, a barrel on the drive shaft and secured thereto, a pinion assembly consisting of a pinion and inner and outer annular walls projecting therefrom longitudinally of the barrel, a spline sleeve on the barrel, spiral grooves on the inner side of the outer wall, spline teeth on one end of the sleeve engageable with the said spiral groove on the outer wall, cushioning means between the walls and against which the toothed end of the sleeve impinges, and a splined spiral connection between the barrel and the said sleeve.

2. A starter drive comprising a drive shaft, a barrel on the drive shaft and secured thereto, a pinion assembly consisting of a pinion and inner and outer annular walls projecting therefrom longitudinally of the barrel, a spline sleeve on the barrel, spiral grooves on the inner side of the outer wall, spline teeth on one end of the sleeve engageable with the said spiral groove on the outer wall, cushioning means between the walls and against which the toothed end of the sleeve impinges, and a splined spiral connection between the barrel and the said sleeve, said cushion member between the walls consisting of an annulus of cushion rubber and a metallic gasket between the sleeve and the said annulus.
3. A starter drive comprising a drive shaft, a barrel on the drive shaft and secured thereto, a pinion assembly consisting of a pinion and inner and outer annular walls projecting therefrom longitudinally of the barrel, a spline sleeve on the barrel, spiral grooves on the inner side of the outer wall, spline teeth on one end of the sleeve engageable with the said spiral groove on the outer wall, cushioning means between the walls and against which the toothed end of the sleeve impinges, and a splined spiral connection between the barrel and the said sleeve, and a lock ring on the inside of the outer wall for preventing displacement of the toothed end of the sleeve.
4. A starter drive comprising a drive shaft, a barrel on the drive shaft and secured thereto, a pinion assembly consisting of a pinion and inner and outer annular walls protecting therefrom longitudinally of the barrel, a spline sleeve on the barrel, spiral grooves on the inner side of the outer wall, spline teeth on one end of the sleeve engageable with the said spiral groove on the outer wall, cushioning means between the walls and against which the toothed end of the sleeve

impinges, and a splined spiral connection between the barrel and the said sleeve, said spiral splined connection between the sleeve and the barrel consisting of spiral grooveways on the inner side of the sleeve and removable radially disposed pins on the barrel engaging into the said grooveways of the sleeve. 5

5. A starter drive comprising a drive shaft, a barrel on the drive shaft and secured thereto, a pinion assembly consisting of a pinion and inner and outer annular walls projecting therefrom longitudinally of the barrel, a spline sleeve on the barrel, spiral grooves on the inner side of the outer wall, spline teeth on one end of the sleeve engageable with the said spiral grooves on the outer wall, cushioning means between the walls and against which the toothed end of the sleeve impinges, and a splined spiral connection between the barrel and the said sleeve, and a removable abutment at one end of the barrel 20 against which the said pinion can abut.

6. A starter drive comprising a drive shaft, a barrel on the drive shaft and secured thereto, a pinion assembly consisting of a pinion and inner and outer annular walls projecting therefrom longitudinally of the barrel, a spline sleeve on the barrel, spiral grooves on the inner side of the outer wall, spline teeth on one end of the sleeve engageable with the said spiral groove on the outer wall, cushioning means between the walls and against which the toothed end of the sleeve impinges, and a splined spiral connection between the barrel and the said sleeve, and a removable abutment at one end of the barrel 30 against which the said pinion can abut, said abutment being of sectional and demountable construction. 35
